UNITED STATES PATENT OFFICE.

GEORGE F. DILLIG, OF BALTIMORE, MARYLAND.

EXPLOSIVE-ENGINE.

1,092,205.

Specification of Letters Patent.

Patented Apr. 7, 1914.

Application filed April 9, 1912. Serial No. 669,499.

To all whom it may concern:

Be it known that I, GEORGE F. DILLIG, a citizen of the United States, residing at Baltimore, in the State of Maryland, have invented certain new and useful Improvements in Explosive-Engines, of which the following is a specification.

This invention relates to improvements in explosive engines.

10 The invention consists of the novel construction and arrangement of the parts and combination of parts hereinafter more fully set forth in the following specification and pointed out in detail in the claims.

15 In the accompanying drawings,—Figure 1 is a front view of an explosive engine having my invention applied thereto. Fig. 2 is an end view of Fig. 1, partly broken away, and showing a vertical section of one of the 20 pistons and differential cylinders. Fig. 3 is a detail view, on an enlarged scale, of one of the differential pistons. Fig. 4 is a vertical sectional view of the differential piston on the line X—X of Fig. 3.

25 In the present instance I have shown my invention as applied to a two-cycle, four cylinder engine, and as each cylinder and the parts contained therein are identical in construction and operation, I have only 30 shown the operative parts of one cylinder, the description of which applies to the said parts in the other three cylinders.

Referring to the accompanying drawings, forming part of this specification, and in 5 which like reference numerals designate like parts throughout the several views thereof, 1 designates the crank case in which is mounted the crank-shaft 2. The differential cylinders 3 are bolted to the crank-case 1 and 0 are open at their inner ends to the crank-chamber 1, and are also provided with circumferential ports 4 communicating with 5 said crank-chamber 1. The outer end of each differential cylinder 3 is provided with 10 an exhaust port 5 which communicates with the exhaust manifold 7, and through which the burnt gases exhaust to the atmosphere. Each of the said ports 5 is provided with 15 an exhaust valve 6 which is held to its normal, or seated, position by the spring 8 surrounding the stem of the said valve, which stem projects through the end of the cylinder 3 and has its outer end impinging against one end of the rock-arm 9, which latter is mounted in the bearing 10 and is connected at its opposite end to the rod 11.

The rods 11 are operated by the cams 12 on the shaft 13, to which latter power is transmitted through the gears 14, 15 and 16, the latter being mounted on the crank-shaft 2. 5 The differential cylinders 3 are each provided with a differential piston 17, the large inner end of which acts as a compressor and pump, and are each connected to the crank-shaft 2 by means of a piston rod 18. The 10 pistons 17 are each provided with a chamber 19 in its outer end formed by the solid partition 20, said chamber having an opening 21 leading therefrom to the combustion chamber 22, said opening being provided with a 15 valve 23 which is held to its normal, or seated, position by the spring 24. The chambers 19 are also provided with integral radiating ribs 25 which absorb sufficient of the heat caused by the firing in the combustion 20 chamber 22 to prevent the overheating of the piston, and which heated ribs serve to assist the complete vaporization of any liquid hydro-carbon which may be carried 25 into said chamber with the incoming charge. 30 The pistons 17 are turned down, or contracted, on their outer surfaces, just back of the piston rings 26 to the inner end to form an annular passage 27 between said piston and the differential cylinder 3 for the 35 passage of the charge from the crank-chamber 1 to the combustion chamber 22. The 40 said charge passes through the ports 4, passage 27 and ports 28 to the chamber 19 and from thence through the opening 21 to the 45 combustion chamber 22. The differential cylinders 3 are each provided with a relief 50 port 29 the purpose of which will herein-after more fully appear, and also a water jacket 30. The carburetor 31 is secured to 55 the crank case 1 and has communication with the crank chamber.

The operation of my invention is as follows: The differential piston 17, as shown in Fig. 2 of the drawing, is at the limit of 60 its upward stroke with the gas compressed in the combustion chamber 22 at the position of firing. As soon as the firing takes place the piston 17 begins to travel down causing a partial vacuum in the large end of 65 the differential cylinder 3, which, when the 70 large rear end of the piston 17 passes the ports 4, causes a charge of gas to be drawn through the said ports 4 to the said large end of the differential cylinder 3 then to the 75 passage 27 and through the ports 28 to the 80 chamber 19. The exhaust valve 6 is opened 85

mechanically, as heretofore described, shortly before the piston 17 completes its downward stroke, which allows the burnt gases to exhaust from the combustion chamber 22 through the exhaust valve to the exhaust manifold 7 and then to the atmosphere. The said valve 6 remains open for a portion of the up stroke of the piston 17 which assists in dispelling any of the burnt gases which may remain in the combustion chamber. As the said piston 17 travels up it begins to compress the charge taken in through the ports 4 causing it to unseat the valve 23 against the action of the spring 24 and allowing the gas to flow to the chamber 22, the exhaust valve remaining open the incoming fresh charge forces any remaining burnt gases from the combustion chamber 22 through the exhaust valve to the exhaust manifold 7 and thence to the atmosphere; thereby assuring a full fresh charge at each stroke of the piston. The said exhaust valve 6 is then closed and the piston 17 continues its upward travel and compression of the charge. The valve 23 will remain open until the large rear end of the piston 17 passes the relief port 29 which allows the gas back of the valve 23 to escape to the rear of the differential cylinder 3, thus relieving the pressure back of said valve 23 and allowing the latter to seat. The piston 17 then completes its upward stroke and final compression of the charge in the combustion chamber, occupying the position shown in Fig. 2 ready for another firing. Each time a charge is drawn into one of the differential cylinders 3 from the crank chamber 1 a similar charge will be drawn from the carburetor into the crank chamber 1, but is not compressed therein.

Having thus described my invention, what I claim is:

1. An explosive engine comprising a crank-case, a crank-shaft mounted in said case, a differential cylinder having communication with the crank-case and having an exhaust port in its outer end, a differential piston having a chambered outer end, a passage between the ends of the piston, and ports leading from the chamber in the outer end of the piston to said passage, a valve to control communication between the chamber in the piston and the combustion chamber, and means connecting said piston with the crank-shaft.

2. An explosive engine comprising a crank-case, a crank-shaft mounted in said case, a differential cylinder having communication with the crank-case and provided with an exhaust port in its outer end, a differential piston having a chambered outer end, a passage between the ends of the piston, and ports leading from the chamber in the end of the piston to said passage, said chamber being provided with

a number of radiating ribs and an opening leading to the combustion chamber, a valve to control communication between the piston chamber and the combustion chamber, and means connecting the piston with the crank-shaft.

3. An explosive engine comprising a crank-case, a crank-shaft mounted in said case, a differential cylinder provided with an exhaust port in its outer end and a number of annularly disposed ports in its inner end communicating with the crank-chamber, a differential piston having a chambered outer end and turned down, or contracted, on its outer surface between the ends thereof to form a passage between the piston and the differential cylinder and a number of annularly disposed ports leading from the said passage to the chamber in the end of the piston, a valve to open and close communication between the chamber in the end of the piston and the combustion chamber, and means connecting said piston with the crank-shaft.

4. An explosive engine comprising a crank case, a crank-shaft mounted in said case, a differential cylinder provided with an exhaust port in its outer end and a number of annularly disposed ports in its inner end communicating with the crank chamber, a differential piston having a chambered outer end, and turned down, or contracted, on its outer surface between the ends thereof to form a passage between the piston and the differential cylinder and a number of annularly disposed ports leading from said passage to the chamber in the end of the piston, said chamber being provided with a number of integral radiating ribs and an opening leading to the combustion chamber, a valve to control communication between the said piston chamber and the combustion chamber, and means connecting the piston with the crank-shaft.

5. An explosive engine comprising a crank-case, a crank-shaft mounted in said crank-case, a differential cylinder having annularly disposed ports in its inner end communicating with the crank-chamber and an exhaust port in its outer end, a differential piston in said differential cylinder provided with a chamber in its outer end having an opening leading to the combustion chamber, and a valve to open and close said opening, said piston being turned down, or contracted, on its outer surface between the ends thereof to form a passage between the piston and the differential cylinder, and annularly disposed ports leading from said passage to the chamber in the end of the piston, a valve to control the opening and closing of said exhaust port, means operated by the crank-shaft for opening and closing said exhaust valve, and means connecting the piston with the crank-shaft.

6. An explosive engine comprising a crank-case, a crank-shaft mounted in said case, a differential cylinder provided with an exhaust port in its outer end and a number 5 of annularly disposed ports in its inner end communicating with the crank-chamber, and a relief port adapted to be opened and closed by the large inner end of the piston, a differential piston having a chambered outer 10 end, and turned down, or contracted, on its outer surface between the ends thereof to form a passage between the piston and the differential cylinder and a number of annularly disposed ports leading from said passage to the chamber in the end of the piston, said chamber being provided with a number of integral radiating ribs, and an opening leading to the combustion chamber, a valve to open and close said opening 15 in the piston chamber, and means connecting said pistons with the crank-shaft.
7. A multiple cylinder engine comprising a crank-case, a crank-shaft mounted in said crank-case, a number of differential 20 cylinders each provided with an exhaust port in its outer end and a number of annularly disposed ports in its inner end communicating with the crank-chamber, a differential piston in each of said differential 25 cylinders each having a chambered outer end, and turned down, or contracted, on its outer surface between the ends thereof to form a passage between the piston and the differential cylinder and a number of annularly disposed ports leading from said passage to the chamber in the end of the piston, said chamber being provided with a number of integral radiating ribs, and an opening leading to the combustion chamber, a valve to open and close said opening 30 in the piston chamber, and means connecting said pistons with the crank-shaft.
8. A multiple cylinder engine comprising a crank-case, a crank-shaft mounted in said case, a number of differential cylinders having communication with the crank-chamber and each provided with an exhaust port in its outer end, a valve for each of said exhaust ports, means operated by the crank-shaft for opening said exhaust valves, a differential piston within each of said differential cylinders provided with a chamber in its outer end having an opening to the combustion chamber, and a valve to open and close said opening, said pistons being turned 35 down, or contracted, on their outer surfaces between the ends thereof to form an annular passage between the piston and the differential cylinder and ports leading from the said piston chamber to the said passage, and means connecting said pistons with the crank-shaft.

In testimony whereof I affix my signature in presence of two witnesses.
